UNITED STATES PATENT OFFICE.

JESSE L. POOLE, OF RICHMOND, VIRGINIA.

ADDING AND SUBTRACTING MACHINE.

1,257,926.

Specification of Letters Patent. Patented Feb. 26, 1918.

Application filed August 25, 1916. Serial No. 116,821.

To all whom it may concern:

Be it known that I, JESSE L. POOLE, citizen of the United States, residing at Richmond, in the county of Henrico and State 5 of Virginia, have invented certain new and useful Improvements in Adding and Subtracting Machines, of which the following is a specification.

My present invention pertains to machines for making calculations; and it has for its general object to provide an adding and subtracting machine that is simple and inexpensive in construction, susceptible of easy manipulation and reliable in operation 10 and equipped with an organized mechanism which embodies no delicate parts such as are likely to get out of order after a short period of use.

The invention in all of its details will be 20 fully understood from the following description and claims when the same are read in connection with the accompanying drawings, forming part of this specification, in which:

25 Figure 1 is a plan view of the adding and subtracting machine constituting the best practical embodiment of my invention that I have as yet devised.

Fig. 2 is a side elevation of the same.

30 Fig. 3 is a fragmentary horizontal section taken in a plane above the actuating belts and working units and illustrating a sufficient number of divisions comprising said elements to make clear the operation of my 35 novel mechanism.

Fig. 4 is a longitudinal vertical section of the machine.

Fig. 5 is a detail section showing some of the idler sprockets on their shaft.

40 Figs. 6 and 7 are details illustrative of the projections on the actuating belts.

Figs. 8 and 9 are detail views of the gears that are equipped with supplemental teeth in the form of lateral projections.

45 Fig. 10 is a fragmentary transverse section, showing in detail the channeled plate that is carried at the underside of the casing top.

Similar numerals of reference designate 50 corresponding parts in all of the views of the drawings.

In the preferred embodiment of my invention the machine casing is made of metal and is characterized by a rounded forward cor-

ner 1 in which are small circular openings 2, 55 and a flat top wall 3 in which are nine (more or less) slots 4; each slot being in longitudinal alinement with one opening 2. There is one of the slots 4 for each division of the machine, and the said slots are respectively 60 divided into equal parts and numbered at their opposite sides; the numbers on the right hand sides serving in the operation of the machine for adding, and the numbers at the left hand sides being designed for use 65 in the reverse direction when the machine is manipulated for subtracting.

Only the first and last slots are shown in Fig. 1 as provided with reversely arranged numbers but it will be understood that in 70 practice all of the slots will be provided with reversely arranged numbers similar to those of the first and last slots.

Fixed to and arranged under the top wall 3 of the casing is a plate 5 in which are 75 grooves 6, one under each slot 4, for the reception and movement of the upper stretches of belts 7 which correspond in number to the slots 4 and the divisions of the machine. The belts 7 are identical in construction and 80 therefore a detailed description of the one shown in Figs. 4, 6 and 7 will suffice to impart a definite understanding of all. The belt 7 referred to is made of any material possessed of the requisite flexibility and durability. It is provided at intervals in its length with apertures 8 for the outward passage of projections 9 which projections form the stems of T members, the transversely disposed heads 10 of which are 85 arranged and suitably fastened against the inner side of the belt and are V shaped in cross section to fit in the interdental spaces of revoluble elements hereinafter described. The projections 9 are adapted to longitudinally traverse one of the slots 4 and are placed a distance apart corresponding to the distance between the graduations or divisions complementary to the slot. By virtue of the stems of the T-members resting in apertures 100 in the belt 7, the T-members assist in connecting themselves to the belt 7 and at the same time take all strain off the fastening means between the heads 10 and the belt, which fastening means may be of any suitable character, when said heads 10 engage the sprocket wheels complementary to the belt.

Formed in the side walls of the machine

casing adjacent to the rear end thereof are slots 11 to receive the rear axle 12 and to permit of the adjustment of the said axle with a view to regulating the tension of the 5 belts 7. On the said axle 12 are loosely-mounted idler sprockets 13, one for each belt 7, and each having ten teeth to engage in the spaces between the belt heads 10. The said idler sprockets are maintained in 10 spaced relation to each other by loose washers 14 interposed between them, and the sprockets adjacent to the side walls of the casing are prevented from contacting with said side walls through the medium of comparatively thin washers 15, Fig. 5.

Within the casing and at points in front of the slots 4 the belts 7 are supported by ten-toothed sprocket wheels 16 of which there is one in each working unit; the said 20 unit comprising in addition to a sprocket wheel 16, a thin plain wheel 17 to the left of the sprocket wheel 16, a gear wheel 18, having ten teeth or a multiple of ten teeth, at the left of the plain wheel 17, and a lateral extension 19 toward the left on a tooth or teeth of the gear wheel 18; the said tooth or teeth of the extension being equal to one tenth of the number of teeth in the gear wheel attached to the right hand side of 30 the number-ring in front of and at the left of the working unit just described. The extension 19 referred to will upon each revolution of its sprocket wheel 16 come into gear with the gear wheel attached to the right hand side of the next higher number-ring and move said number-ring through one-tenth of its circumference. The said 35 sprocket wheel 16, plain wheel 17, gear wheel 18 and lateral extension 19 of each 40 working unit are securely fastened together, and the said working units are maintained in proper relation on a transverse shaft 20 by spacing washers 21 and 21^a. It will thus be seen that the working units referred to 45 constitute a transverse section of elements in which there are sprocket wheels 16 corresponding in number to the slots 4 and the belts 7; also, that the washers 21^a are next to the side walls of the casing.

50 In front of the transverse section of elements described there is another transverse section or series of working units on a transverse shaft 22. Of these working units at the front of the machine, the one toward the 55 right or in the first division of the machine is made up of a thin plain wheel 23 at the right, a number-ring 24 *i. e.*, a ring bearing numbers on its perimeter, in the middle, and a gear wheel 25 at the left, these elements 60 being fixed together, and the gear wheel having ten teeth or a multiple of ten teeth and being intermeshed with the gear wheel 18 of the first working unit toward the right of the previously described transverse 65 section or series of working units. All of

the other working units in the front section or series with the exception of the one at the left, Fig. 1, are respectively made up of a number-ring 24^a in the middle, and gear wheels 25^a fixed at opposite sides of the number-ring 24^a and each having ten teeth or a multiple of ten teeth. The said working unit at the left of the section or series, Fig. 1, has a gear wheel 25^a at the right of its number-ring 24^a but none at the left of said number-ring. Thin washers 26 are provided between the working units of the front section or series of the machine, to prevent contact during the working of the machine. I would also have it understood that the 80 number-rings each bear the numerals 0—9, and that in the front transverse section or series as in the second transverse section or series from the front there is one working unit in each division of the machine—*i. e.*, 85 one working unit in longitudinal alinement with each slot 4 and each belt 7, and so arranged that the numerals on the number-rings are displayed through the casing openings 2 which openings may be glazed or left 90 unglazed in the discretion of the manufacturer of the machine. I would further have it understood that it is manifestly unnecessary to have an extension 19 on the gear wheel 18 at the left of the second transverse 95 section or series of elements from the front.

My novel machine is actuated through the medium of the belts 7, the belts being moved as desired by an implement engaged with one of the belt projections 9 and 100 moved in one of the casing slots 4.

Incidental to the operation of the machine in adding and subtracting, it will be manifest that the working units in the second transverse section or series from the front 105 will be actuated directly by the belts, and will, in turn actuate the working units in the front transverse section or series in the manner and for the purpose described.

I have entered into a detailed description of the construction and relative arrangement of the parts comprised in the present and preferred embodiment of my invention in order to impart a full, clear and exact understanding of the said embodiment. I do not desire, however, to be understood as confining myself to the said specific construction and relative arrangement of parts as in the future practice of the invention such changes or modifications 115 may be made, as fairly fall within the scope of my appended claims.

For instance the machine may embody any desired number of divisions according to the work for which it is especially designed; also, any suitable means may be employed to support the rear portions of the actuating belts so long as the said means is compatible with the purpose of my invention. I would further have it under- 125 130

stood that the numerals and the number rings may be varied as needed to meet different contingencies and that various minor details of construction may be changed as are expedient in practice.

Having described my invention, what I claim and desire to secure by Letters Patent is:—

1. In a calculating machine, the combination of suitably supported sprocket wheels having spaced recesses in their peripheries, a belt surrounding said sprocket wheels and having spaced apertures, and T-members having stems extending outwardly through said apertures of the belt to form finger pieces, and also having transverse heads fastened to the inner side of the belt and adapted to seat in the recesses of the sprocket wheels; the extension of the stems through the apertures of the belt serving to assist in the connection of the T-members to the belt and to take strain off the fas-

tening means between the transverse heads and the belt.

2. In a calculating machine, the combination of suitably supported sprocket wheels having spaced recesses, of V-shape in cross-section, in their peripheries, a belt surrounding said sprocket wheels and having spaced apertures, and T-members having stems extending outwardly through said apertures of the belt, to form finger pieces, and also having transverse heads, of V-shape in cross-section, fastened to the inner side of the belt and adapted to seat in the recesses of the sprocket wheels, for the purposes set forth.

In testimony whereof I affix my signature in presence of two witnesses.

JESSE L. POOLE.
